UNITED STATES PATENT OFFICE.

CHARLES A. BERRY, OF STAMFORD, CONNECTICUT, ASSIGNOR TO THE YALE & TOWNE MANUFACTURING COMPANY, OF STAMFORD, CONNECTICUT.

DOOR CHECK AND CLOSER.

1,254,877.

Specification of Letters Patent. Patented Jan. 29, 1918.

Application filed November 8, 1916. Serial No. 130,199.

To all whom it may concern:

Be it known that I, CHARLES A. BERRY, a citizen of the United States, and a resident of Stamford, in the county of Fairfield and State of Connecticut, have invented certain new and useful Improvements in Door Checks and Closers; and I do hereby declare the following to be a full, clear and exact description of the invention, such as will enable others skilled in the art to which it appertains to make and use the same.

This invention relates to improvements in door checks and closers and more particularly to a safety device employed in conjunction therewith, the object of the invention being to provide and conveniently locate fusible means for controlling the release of the door holding means in the event of a fire, and thus cause the automatic closing of the door by the operation of the release of the door closing means.

With this and other objects in view, the invention consists in certain novel features of construction and combinations of parts as hereinafter set forth and pointed out in the claims.

In the accompanying drawings; Figure 1 is a view of a door check and closer showing an embodiment of my invention; Fig. 2 is a plan view, and Fig. 3 is a detail view of the fusible disk.

1 represents the casing of a door check and closer and 2 the spindle of the same, to which the lever arm 3 is secured,—said lever arm being adapted for coöperation with the mechanism of the device and for connection with the door in the usual manner.

For the purpose of holding the lever arm in position to retain the door temporarily open, the cap or cover 4 of the casing 1 is provided with a lug 5 and serves as a stop with which a spring-pressed dog 6 carried by the lever arm coöperates. The dog 6 may consist of a vertically movable plunger mounted in a boss or enlargement 7 on the lever arm and having a beveled lower end 8. The dog 6 is provided somewhat below its upper end with an annular shoulder 9 and the portion of the dog above this shoulder forms a shank 10,—the upper end which may be elongated in form. A spring 11 is secured at one end to the lever arm 3 by means of a rivet 12, or other suitable fastening means, and the free end of this spring may be provided with a slot 13 to

receive the elongated portion of the shank 10 of the dog.

A fusible or destructible member is disposed between the under face of the spring 11 and the shoulder 9 on the dog and the force of the spring to press the dog downwardly is transmitted to said dog through the medium of said fusible member. The fusible member or destructible member consists of a ring or annular disk 14 of suitable material made to encircle the shank of the dog and rest upon the shoulder 9 and receive the pressure exerted by the spring 11.

A lug or projection 9^a is provided upon the upper surface of the lever arm 3, adjacent the fusible member, to receive the pressure of the spring 11 when the fusible member has been destroyed and at the same time hold the spring 11 in a position sufficiently elevated to allow the dog to rise freely and pass over the lug 5. The upper surface of the lug 9^a should normally be an appreciable distance below the under surface of the spring in order that the pressure of the spring may be exerted upon the dog 6 through the fusible member until such time as the fusible member has been destroyed.

A screw 15 may be secured to the lever arm 3 at a point between its ends and pass freely through a hole in the spring 11, said screw being provided with a nut 16 to bear upon and, by its adjustment on the screw, serve to adjust the tension of the spring.

With the use of a door check and closer embodying my improvements, it will be readily seen that if the door be held open by engagement of the dog 6 with the lug or stop 5, and a fire should occur in the room 95 where the door is located, the fusible member will be broken down, destroyed or melted, and the tension of the spring upon the dog would be at once relieved, so that the lever arm would be released by the dog 6 100 riding past the stop 5, and the door would be automatically closed.

Having fully described my invention what I claim as new and desire to secure by Letters-Patent, is:

1. In a door check and closer, the combination with the casing provided thereon with a stop, the lever arm, a dog carried by the lever arm to engage said stop to hold the door open, and a spring secured to the 110

lever arm and adapted to press the dog toward the casing, of a member destructible by heat disposed between said spring and the dog.

5 2. In a door check and closer, the combination with a casing provided thereon with a stop, a lever arm, and a dog carried by the lever arm to engage said stop to hold the door open, of a spring secured to said arm 10 and adapted to press said dog toward the casing, and a fusible disk disposed between the free end of said spring and said dog.

3. In a door check and closer, the combination with the casing provided thereon with a stop, and a lever arm, of a dog carried by the lever arm to engage said stop to hold the door open, said dog having an 15 annular shoulder and a shank above said shoulder, a spring secured at one end to the lever arm and provided at its free end with

an opening to receive the shank of the dog, and a fusible ring encircling the shank of the dog and disposed between the annular shoulder on the latter and the under face of 25 said spring.

4. In a door check and closer, the combination of a casing, a stop thereon, a lever arm, a dog carried by the lever arm to engage said stop, a spring secured to the lever 30 arm, a fusible member between the free end of said spring and said dog, and a lug on the lever arm to receive said spring when the fusible member has been reduced by heat.

In testimony whereof I have signed this specification in the presence of two subscribing witnesses.

CHARLES A BERRY.
